UNITED STATES PATENT OFFICE

PHILETUS J. STEPHENS, OF NEW YORK, N. Y.

IMPROVEMENT IN EYE-CUPS.

Specification forming part of Letters Patent No. **158,224**, dated December 29, 1874; application filed June 25, 1874.

To all whom it may concern:

Be it known that I, PHILETUS J. STEPHENS, of New York city, county and State of New York, have invented certain Improvements in Eye-Cups, of which the following is a specification:

The object of my invention is to provide for the easier and better working of the so-called eye-cups, or a cup-formed receptacle placed over the eye, and, by aid of a depressed rubber ball attached thereto, producing a suction which acts beneficially to the eye.

My invention consists in the combination, with an eye-cup provided with an india-rubber ball, of an air-relief valve arranged in the neck of the cup and operated by a button or spring.

Figure I is a side view of an eye-cup, embodying my invention. Fig. II is a sectional view of the same.

A is the eye-cup. B is the rubber ring in-

serted in groove *c* of the cup. D is the neck, with hole *e* and valve-seat *f*. *g* is the valve, with stem *h* and button *i*. *j* is the spiral spring encircling the stem *k*, and pressing against the valve at *l* and against the neck at *m*. *N* is the india-rubber ball attached to the neck at *o*.

Having thus described my invention, I desire to claim—

The combination, with an eye-cup, A, provided with a ring, B, neck D, and an india-rubber ball, N, of an air-relief valve, *g*, arranged in the neck D, and operated by a button, *i*, and spring *j*, substantially as shown and described.

PHILETUS J. STEPHENS.
